UNITED STATES PATENT OFFICE.

FREDERICK M. FURBER, OF BEACHMONT, MASSACHUSETTS, ASSIGNOR TO UNITED SHOE MACHINERY CORPORATION, OF PATERSON, NEW JERSEY, A CORPORATION OF NEW JERSEY.

MACHINE AND METHOD APPLICABLE TO THE CUTTING OF SHEET MATERIAL.

Application filed March 10, 1919, Serial No. 281,848. Renewed November 15, 1922. Serial No. 601,179.

To all whom it may concern:

Be it known that I, FREDERICK M. FURBER, a citizen of the United States, residing at Beachmont, in the county of Suffolk and State of Massachusetts, have invented certain Improvements in Machines and Methods Applicable to the Cutting of Sheet Material, of which the following description, in connection with the accompanying drawings, is a specification, like reference characters on the drawings indicating like parts in the several figures.

This invention relates to machines and methods for use in the cutting of sheet material and more particularly to the production of blanks in quantity from sheet material. The invention is herein exemplified with special reference to the cutting of heel lifts, but it is to be understood that in various aspects the invention is not so limited but is applicable to the production of analogous blanks and parts.

Heretofore in attempting to secure the economical production of heel lifts, soles, and similar blanks in quantity, a plurality of dies shaped to correspond to the blanks desired have been arranged to cut simultaneously through the selected material, with results not entirely satisfactory from the standpoint of economy of power and of material. Since the walls of the dies have appreciable thickness and the compressibility of the material operated upon and located between the dies is limited, the dies must be spaced a certain distance apart with the result that considerable scrap material is produced along with the blanks. Moreover, for forcing a set of dies through sheet material such as sole leather, leather-board, heavy paper board, and composition sheet material, machines ordinarily of great weight and strength must be constructed capable of developing power sufficient to the requirements of the work. The compression of the material between the dies adding to the frictional drag of the material upon the dies as the latter are forced through the material is a big factor in the resistance encountered during cutting operations under the conditions described. It has been proposed to force a single die through a plurality of superposed layers of material. Here again the expenditure of power is very great and increases

rapidly with each added layer of material, while the rate of the work feeding and cutting operations is likely to decrease with the increase of layers in the work and of weight in the machine. 55

It is an object of the present invention to provide a method of cutting blanks from sheet material, the practice of which will be generally more satisfactory and economical than methods heretofore employed. 60

Accordingly, in one aspect, the invention comprises the presentation of sheet material with respect to a plurality of dies in such manner that a minimum of waste or scrap material is produced in the dieing-out operations. 65

To this end, adjacent sections of a row of sections of sheet material are moved laterally in opposite directions into position over dies. Dieing out operations are then performed simultaneously on all of the sections to produce blanks of a width substantially equal to the width of a section. 70

The invention contemplates also the cutting of sheet material into sections or blanks in such manner as to utilize a previously cut section or blank as a cutting bed for a succeeding cutting operation, thus insuring clean cutting of the sections or blanks and at the same time avoiding any mutilation of the cutting means and the co-operating work supporting structure. In this aspect the method comprises the positioning of sheet material to be cut on top of a piece of material already operated upon. Preferably, prior to a cutting operation, the lowermost cut sections are removed from the bottom of the pile, cutting operations being performed in properly timed relation with respect to the introduction and removal of work. Such a procedure has the marked advantage of being practicable in the use of the simplest types of completely automatic machinery. 80 85 90 95

In its machine aspect, a feature of the invention comprises a novel arrangement of dies in a cutting machine by which it is possible in operating upon sheet material to cut simultaneously a plurality of blanks as closely adjacent in the sheet as if the dies were in contact with each other and had walls of no appreciable thickness. 100

Other features of importance relate to novel constructions in a cutting machine op- 105

erative to cut into sections sheets of material at the top of a pile of sheets and to remove sections from the bottom of the pile progressively with the cutting operations.

5 Other features and objects of the invention will be apparent from the following detailed description and will be pointed out in the claims.

In the drawings:—

10 Fig. 1 is a perspective view partly in section of a multiple die cutting machine;

Fig. 2 is a diagrammatic plan view showing the arrangement of the dies and of the feeding members for the sections of sheet 15 material; and

Fig. 3 is a section of a portion of the machine taken along the line 3—3 of Fig. 2.

In the illustrative machine there is disclosed one embodiment of the invention 20 which may be used in practicing the novel method of cutting sheet material into blanks described in detail and claimed in this application. As disclosed the machine comprises a work support 6 upon which sheet material rests during cutting operations 25 effected by means of severing knives 8 arranged in regularly spaced relation upon a crosshead 10. Preferably sheets or strips of stock will be fed by suitable means (not 30 shown) from a magazine (not shown) into position on a work support or table 6, a gage 12 being provided at one end of the table for determining the correct location of the strips for the cutting operation. According 35 to the arrangement disclosed the strips are cut into sections of uniform size while they are supported by a strip which has already been cut into sections, this arrangement being for the purpose of providing a fresh 40 cutting bed for each strip or set of strips that is cut, and of preventing mutilation of the knives 8 or of the work support 6 during cutting operations. It is necessary, in starting the operation of the machine for 45 the first time, to position sections of the proper size on the cutting bed 6. Thereafter the machine operates on fresh strips placed on top of the previously sectioned strip or strips and removes the bottom sectioned strip after each succeeding cutting 50 operation. By this removal a freshly cut or sectioned strip is deposited upon the table 6 and serves as a cutting bed for the succeeding sheet or strip of material so that the cutting edges of the knives 8 pass through the strip being cut and into the spaces between adjacent sections. The bottom sections are removed from the table 6 by suitable means comprising in the illustrative machine, 55 forked feeding members 14 which have fingers 16 so arranged as to feed adjacent sections in opposite directions as the feeding members approach each other. Preferably the feeding members are simultaneously operated by means comprising shafts 60

17. In order to effect the feeding operation, the fingers of the two feeding members 14 are staggered relatively to each other and pass into interlocking arrangement across the work supporting table 6. As the sections 18 leave the table 6 they pass over the upper open ends of dies 20. These dies are of sufficient size to form heel lifts having maximum width approximately equal to the width of a section of material, and are made 70 hollow in order to receive lifts as they are died out. The dies 20 are arranged in two rows one on each side of the table 6 and spaced from each other in the row a distance corresponding approximately to one dimension of the sections. This dimension is also practically equivalent to a transverse dimension of the dies so that, if the two rows of dies were moved directly toward each other 80 until the dies were all arranged in one row, each die would be in contact with each adjacent die. In other words, by this arrangement of dies blanks are cut so from the sections of sheet material as to leave practically no scrap material at the sides of the 85 sections. Since it is not possible in a practical machine to arrange the dies so closely together in one row, the arrangement adopted has the advantage of effecting the same saving of material by cutting blanks with as little waste as would occur if they were cut in a hypothetical machine having dies arranged in contact with each other. 90

In pushing the sections of the lowermost strip from the supporting table 6, it is obvious that sections above and resting on the lowermost sections would be displaced laterally were no means provided for preventing such displacement. As shown, holding or retaining members 22 are provided 100 detachably mounted on side bars 24 and having flanged ends 26 disposed in such a way as to prevent movement laterally of all but the lowermost sections which rest on the table 6. While the flanged ends 26 of the 105 retaining members are shown to present plane faces toward the medial line of the table, it is clear that said faces may be curved, especially at the ends thereof, in order more readily to guide the uncut strips 110 of material as they are fed from the magazine on to the work supporting table. After the sections 18 have been positioned over the dies 20, relative movement between the 115 said dies and co-operating blocks or presser members 28 is effective to cut or die out heel lifts from the sections. In the illustrative machine crosshead members are provided at opposite ends of the work support 6 for carrying the crosshead 10 and presser members 28. One of the crosshead members is shown at 30, and is adapted to be reciprocated upon guides 31 by means of any suitable mechanism. Upon downward movement of the crosshead members, a strip or 120

125

130

set of strips of material is severed into sections and simultaneously a set of sections are died out into blanks by being forced through the stationary dies 20. Before the 5 first operation of the machine sections are placed upon the upper edges of the dies 20 and at the first reciprocation of the blocks 28 the said sections are forced only partway into the dies. Subsequent operations of the 10 blocks 28 force the partly cut sections through the dies and leave other sections partly cut through on the upper edges of the dies as indicated in Fig. 3. By this arrangement the cutting edges of the dies 15 never come into contact with the faces of the blocks 28 so that there is no injury or mutilation of these co-operating surfaces in the machine. Moreover, by this arrangement the sections as they are cut are provided successively with constantly new cutting bed surfaces in the succeeding sections so that the edges of the cut blanks are 20 always cleanly cut. The removal of the scrap material which, in the present instance, is reduced to a minimum is insured 25 by means including blades 32, each die having two blades located oppositely to each other and having their sharp edges in the same plane as the cutting edge of the die. 30 Thus, as a section is cut to make a blank, the surrounding portion of scrap material is severed at two points so that it readily falls away from the die while the blank passes through the die into a magazine or other 35 receptacle provided for the purpose. As the scrap material leaves the die it falls upon a plate 34 having portions inclined in opposite directions from which the scrap slides to the floor or to a receptacle provided to 40 receive such material, the said inclined plate, in the structure disclosed, forming part or all of the support for the dies 20.

In practicing the method of cutting sheet material herein disclosed by means of a machine such as that illustrated in the drawings, strips of material are fed into the machine from the right against a gage such as that shown at 12 and the machine is operated to cut the strips into sections while the 45 previously cut or sectional strip serves as a cutting bed during the cutting operations. It is clear that this method has the marked advantage of simplicity in the steps involved since the fresh sheets of material to be operated upon are fed always on top of those previously positioned in the machine and the cut or sectioned strips are removed from the bottom of the pile, no other positioning or rearranging of the strips being 50 necessary.

A further marked advantage of the invention, in its practical application, resides in the feeding of the sections of strips in opposite directions, since by this arrangement 55 the sections may be cut very close to

the size of the desired blank. These sections may then be cut into blanks by the use of dies arranged in such a way with relation to each other that the arrangement is the equivalent of dies in a single row in close 70 contact with each other throughout, thus making it possible to cut sheet material into blanks with the accompanying production of little or no scrap or waste material.

It should be pointed out that my invention 75 contemplates the cutting of a plurality of sheets or strips at one time into sections while other previously cut or sectioned strips serve as a cutting bed, and then feeding a plurality of sections over each die to 80 have blanks cut therefrom. Thus, the invention is not limited in any way by the disclosure of the specific machine which, indeed, is illustrative only of one embodiment of mechanism for practicing the novel 85 method of the invention, the breadth of the invention being determinable by the scope of the appended claims.

Having thus described my invention, what I claim as new and desire to secure by 90 Letters Patent of the United States is:

1. In a cutting machine, a support for a pile of sheet material, means for cutting the sheets of material on the support to form sections from the sheet material, and 95 means for feeding sections from the bottom of the pile between successive operations of said cutting means on material at the top of the same pile.

2. In a cutting machine, a support for a pile of sheet material, a crosshead above the support carrying knives arranged to cut transversely of material on the support to form sections from the sheet material, and means for feeding sections from the bottom 105 of the pile between the operations of cutting sections at the top of the pile.

3. In a cutting machine, a support for the sheet material to be cut, means for severing the sheet material into sections, dies arranged in rows upon opposite sides of said support, means for simultaneously moving adjacent sections in opposite directions into position over said dies to have blanks cut therefrom, and presser members for cooperating with the dies in cutting operations 110 on the sections.

4. In a cutting machine, a support for the material to be cut, a crosshead carrying knives to sever the material into sections, dies arranged in rows on opposite sides of the work support, means for feeding adjacent sections in opposite directions over said dies, and presser members movable relatively to the dies for cooperating with the 115 dies to effect cutting operations on the sections.

5. In a cutting machine, a support for the material to be cut, a crosshead carrying knives to sever the material into sections by 120

- transverse cuts, dies arranged in rows on opposite sides of the work support, means for simultaneously feeding adjacent sections in opposite directions over said dies, and 5 presser members movable with the cross-head for cooperating with the dies to effect the cutting of the sections by the dies.
6. In a cutting machine, a work support, means for cutting the material supported 10 on the work support into sections, dies arranged in rows upon two sides of the work support, the dies in each row being spaced apart a distance corresponding to the dimension of a die in the direction of the row, 15 means for positioning the sections over the dies to have blanks cut therefrom, and a presser member for each die, said presser member and die being relatively movable to effect the cutting of a blank from a section. 20
7. In a cutting machine, a work support, means for cutting the material supported on the work support transversely into sections, dies arranged in rows upon two sides 25 of the work support, the dies in each row being spaced apart a distance corresponding to the dimension of a die in the direction of the row and being so arranged that the dies in one row are exactly opposite the 30 spaces in the other row, and means for positioning the sections over the dies to have blanks cut therefrom. 35
8. In a cutting machine, a work support for a pile of sheet material to be cut, means for severing sheets of material into sections 40 while supported on said work support, said means and said work support being relatively movable toward and from each other to cut the material and so constructed and arranged as not to contact with each other during the cutting operations, and means for feeding sections from the bottom of the pile in the intervals between the cutting of sheet material positioned on the top of the 45 same pile. 50
9. In a cutting machine, a work support for material to be cut, means for severing sheets of material into sections, means for removing the lowermost sections, and means 55 for preventing removal of sections above the lowermost sections, the arrangement being such that upper sections drop down upon the removal of the lowermost sections to serve in turn as a cutting bed to co-operate 60 with the first mentioned means during cutting operations upon subsequent sheets of material. 65
10. In a cutting machine, a work support for material to be cut, means for cutting 70 into sections sheets of material positioned on said support, a row of dies at one side of said support, means for moving the sections from the support into position over the dies, and means for co-operating with 75 said dies to cut blanks from the sections and simultaneously insure the removal of scrap progressively with the dieing out operations. 80
11. In a cutting machine, a work support for material to be cut, means for sectioning the material on said support, dies arranged in rows on two sides of said support, said dies being spaced apart in each row a distance equal to one dimension of the sections formed in the sectioning operation, means for feeding sets of sections in opposite directions into position over said dies, means to co-operate with said dies in dieing out blanks from said sections, and means for insuring the removal of waste or scrap material simultaneously with the dieing out operations. 85
12. In a cutting machine, a support for material to be cut, means for cutting into sections sheets of material supported on 90 said support, a row of dies at one side of said support, a plate surrounding each die and inclined away from the work support, means for moving the sections from the work support and into position over said dies, means for co-operating with said dies to die out blanks from said sections, and means including said inclined plate for insuring the removal of scrap material from 95 the dies. 100
13. In a cutting machine, a work support for supporting a pile of sheets of material to be cut, means for cutting through upper sheets in the pile, the construction being such that the sections thus cut are removed from the bottom of the pile, a row of dies at one side of the work support, means for moving a set of sections from the bottom of the pile into position over said dies, and means to co-operate with said dies for dieing 105 out blanks from the sections, the construction and arrangement being such that the sections are died only partway through at one operation and completed at the second operation after fresh sections have been 110 placed over those partly died out at the first operation. 115
14. That improvement in methods of cutting blanks from sheet material which comprises cutting each sheet of material into sections or blanks in such manner as to leave the sections or blanks in the same plane as the original sheet, and simultaneously utilizing a sheet, cut or sectioned in the manner described during a preceding operation, as a cutting bed for a succeeding sheet undergoing cutting operations of the same character. 120
15. That improvement in methods of cutting blanks from sheet material which comprises cutting each sheet of material into a plurality of sections or blanks in such manner that after the cutting operation the latter are in the position occupied by the sheet prior to said operation, placing other sheet 125 130

or sheets on top of the sectioned sheet or sheets, and proceeding to cut the fresh sheet or sheets while utilizing the cut or sectioned sheet or sheets as a cutting bed during the 5 cutting operations.

16. That improvement in methods of cutting blanks from sheet material into a plurality of blanks or sections in such manner that the blanks or sections remain in the 10 plane of the original sheet which comprises cutting a sheet of material, positioning a fresh sheet above the cut or sectioned sheet, performing a cutting operation on the uncut sheet while making use of the cut or sectioned sheet as a cutting bed, and removing the lower set of sections which represent the sheet first cut, thus leaving sections of the second sheet to serve as a cutting bed during cutting operations on another sheet. 15

17. That improvement in methods of cutting blanks from sheet material which comprises cutting sheets of material into sections having an edge to edge relationship and simultaneously utilizing each freshly sectioned sheet as a cutting bed for each succeeding sheet or set of sheets during cutting operations thereon in such manner that the edge of the cutter passes into the space between the sections which constitute the cutting 25 bed, removing sectioned sheets from the bottom of the pile, and positioning another sheet or set of sheets, over the sectioned sheet or sheets left in position after the removal of sections from the bottom of the pile, for another cutting operation. 30

18. That improvement in methods of cutting blanks from sheet material which comprises cutting sheets into sections and simultaneously making use of previously cut sections arranged edge to edge in one plane as a cutting bed during cutting operations on the first-mentioned sheets, removing the lowermost set of sections and placing them in position over dies to have blanks cut therefrom, forcing said sections on to the dies by relative movement between the dies and said sections, each section being only partly died-out at the first operation, and then completing the dieing-out of said section at a subsequent operation at which time a succeeding section is partly died-out. 45

19. That improvement in methods of cutting blanks from sheet material which comprises supporting a sheet upon previously 55 formed blanks arranged edge to edge in one plane, and cutting the sheet into blanks similar to those previously formed in such manner that the cutting edge of the cutter passes through the sheet being cut and into the space between adjacent blanks forming the support for the sheet. 60

20. That improvement in methods of cutting blanks from sheet material which comprises cutting strips into sections so that the 65 sections lie side by side in a plane, displac-

ing adjacent sections in opposite directions into position over dies, and cutting blanks from said sections.

21. That improvement in methods of cutting blanks from sheet material which comprises cutting sheet material into strips, sectioning the strips by transverse cuts, moving the sections thus formed in opposite directions over dies, and proceeding to cut blanks from the sections by the operation of said dies. 70

22. That improvement in methods of cutting blanks from sheet material which comprises cutting sheets into sections which approximate closely in size the blanks that it is desired to cut therefrom, feeding adjacent sections in opposite directions into position over dies in two rows and spaced in each row a distance equal to a dimension of the section, and proceeding to cut blanks from said sections by the operation of said dies. 80

23. In a cutting machine, a support for sheet material, means for operating on a sheet of material to cut it into a set of blanks while it is supported in a given plane by the blanks of a sheet cut in a previous cutting operation, and means reciprocable along the support during each cycle of the machine for removing the lowermost set of blanks. 90

24. In a cutting machine, a support for sheet material, means for operating on top of a pile of sheets to cut blanks therefrom while the material is supported in a given plane, and means for removing blanks from the bottom of the pile. 95

25. In a cutting machine, a support for the material to be cut, a cross-head carrying knives to cut the material into sections, cutting means comprising dies arranged in rows on opposite sides of the cross-head, and means for feeding adjacent sections in opposite directions into positions to be cut by said dies. 105

26. In a cutting machine, a work support, means for cutting material supported on the work support transversely into sections, dies arranged in rows upon opposite sides of the cutting means, the dies in each row being spaced apart a distance corresponding to the dimension of a die in the direction of the row and being so arranged that a die in one row is exactly opposite a space in the other row, and means for positioning the sections to have blanks cut therefrom by said dies. 110

27. That improvement in methods of cutting sheet material which comprises cutting a sheet into a plurality of blanks while it rests in a given plane at the top of a pile of material, and at intervals withdrawing the cut material at the bottom of the pile whereby the cut material serves as a cutting bed for fresh uncut material. 115

28. In a machine of the character described, a plurality of dies, feeding means for moving a piece of material to one die, 120

130

and a second feeding means for moving a piece of material in the opposite direction to another die, and means for rendering the dies effective to cut blanks from the pieces of material.

29. In a machine of the character described, cutting means for cutting sheets of material into sections of predetermined size, and means comprising a plurality of dies for dieing out blanks simultaneously from different sections.

30. In a machine of the character described, cutting means for cutting a sheet of material simultaneously into a plurality of sections of predetermined size, and means comprising a plurality of stationary dies for dieing out blanks from different sections.

31. In a machine of the character described, means for cutting sheets of material into sections, means for operating on the sections comprising a plurality of dies, and means for simultaneously feeding sectioned material to the several dies.

32. In a machine of the character described, means for cutting sheet material into sections, a plurality of dies, and means for rendering the dies simultaneously effective to cut blanks from the sections previously severed from the sheets by the cutting means.

33. In a machine of the character described, means for cutting sheet material into sections, a plurality of dies, means for feeding a plurality of sections simultaneously to the dies, and means for rendering the dies simultaneously effective to cut blanks from the sections.

34. In a machine of the character described, means for cutting sections from sheet material, means comprising a plurality of dies for operating on the material of the sections, and feed members movable in opposite directions for moving sheet material of the sections into position over the dies.

35. In a machine of the character described, means for cutting sections from sheet material, a plurality of dies for operating on the material of the sections, feeding means simultaneously operable for positioning the material of the sections in dieing-out relation with the dies, and means for rendering the dies simultaneously effective to cut blanks from the sections.

36. In a machine of the character described, means for cutting sections from sheet material, means comprising a plurality of dies for operating on the material of the sections, and feed members movable simultaneously in opposite directions for moving sheet material of the sections into position over the dies.

37. In a machine of the character described, means for cutting sections from sheet material, a plurality of dies for oper-

ating on the material of the sections, feeding means operable for positioning the material of the sections in dieing out relation with respect to two of the dies, and means for rendering the dies simultaneously effective to cut blanks from the sections.

38. In a machine of the character described, a plurality of dies, means for moving sheet material in opposite directions into position over the dies to have blanks cut therefrom, and means for rendering the dies effective to cut blanks from the material.

39. In a machine of the character described, a plurality of dies, a feed member for moving sheet material into dieing out relation to one of the dies, a second feed member for simultaneously moving sheet material into dieing-out relation to a second die, and means for rendering the dies simultaneously effective to cut blanks from the sheet material.

40. In a machine of the character described, a plurality of dies, a feed member for moving sheet material into dieing out relation to one of the dies, a second feed member for simultaneously moving sheet material in an opposite direction into dieing-out relation to a second die, and means for rendering the dies simultaneously effective to cut blanks from the material.

41. In a machine of the character described, a plurality of cutters operative to cut a strip of material into sections, a plurality of dies, and means operable simultaneously with the cutters for forcing such sections upon the cutting edges of the dies to cut blanks therefrom.

42. In a machine of the character described, means for cutting sections from a sheet of material, and means for subsequently cutting blanks from the sections, said means being simultaneously operable for the purposes recited.

43. In a machine of the character described, means for cutting sections from a strip of material, a die and a co-operating press member for dieing out blanks from such sections, said die and said member being relatively movable toward, but not into contact with, each other whereby the die will penetrate only part way through each section during each such relative movement, and means for feeding the sections into position between said die and said member.

44. In a machine of the character described, means including a reciprocating knife for cutting sections from a strip of material, a stationary, upwardly-facing die and a vertically movable cutting block co-operating therewith, a reciprocating member for feeding such sections across the face of the die and beneath said cutting block, said block being movable toward, but not into contact with, the die so that successive sections fed into position on the die are par-

tially cut at each of two successive strokes of the block.

45. In a machine of the character described, cutting means intermittently operative for cutting a sheet of material into sections of predetermined size, and means comprising a plurality of stationary dies for dieing out blanks from the severed sections.

46. In a machine of the character described, means for cutting sheet material

into sections, a plurality of dies having analogous ends pointing alternately in opposite directions, and means for causing simultaneously operation of the dies to cut blanks from the sections severed from the sheets 15 by the cutting means.

In testimony whereof I have signed my name to this specification.

FREDERICK M. FURBER.
